Primary Examiner — Nathan M Johnston*(74) Attorney, Agent, or Firm* — Maschoff Brennan(57) **CLAIM**

The ornamental design for a portion of a delivery tip, as shown and described.

DESCRIPTION

FIG. 1 is a perspective view of a delivery tip showing my new design;

FIG. 2 is a front view of the delivery tip shown in FIG. 1; FIG. 3 is a rear view of the delivery tip shown in FIG. 1; FIG. 4 is a left view of the delivery tip shown in FIG. 1; FIG. 5 is a right view of the delivery tip shown in FIG. 1; FIG. 6 is a top view of the delivery tip shown in FIG. 1; and, FIG. 7 is a bottom view of the delivery tip shown in FIG. 1. The broken lines show portions of the design that form no part of the claimed design.
